UNITED STATES PATENT OFFICE

2,631,659

BURNER ORIFICE SPUD

James A. Wright, Webster Groves, Mo., assignor
to Missouri Automatic Control Corporation, St.
Louis, Mo., a corporation of Missouri

Application March 12, 1951, Serial No. 215,141

2 Claims. (Cl. 158—118)

1

This invention relates generally to gaseous fuel burners and more particularly to a fuel metering and diffusing device for use in connection with gaseous fuel pilot burners.

In the usual pilot burner of simple construction, having a fuel metering orifice, an air injecting means, and mixing conduit of fixed size, the characteristics of the flame at the burner port are affected to a marked degree by variations in fuel velocity at the metering orifice. Inasmuch as commercial fuel supply pressures vary, thereby varying the velocities at the fuel metering orifice, it is desirable to provide means to compensate the effect of these variations so that the optimum flame characteristic may be more closely maintained over a range of fuel pressures.

It has been found that in a burner of the above type, designed to operate efficiently at a particular fuel pressure, suitable diffusion of the fuel stream as it emerges from the fuel orifice compensates for fuel velocity variations and results in suitable burner operation over a range of fuel velocities. The diffusion of the fuel stream is, however, critical and the relationship of the fuel orifice and diffusing means for a given burner must be closely held.

It is the primary object of this invention to provide a unitary device for metering and suitably diffusing a gaseous fuel, which is of simple and economical construction and adapted to convenient detachable assembly with a pilot burner.

A further object is to provide a unitary construction including a single thin plate fuel metering orifice and a fuel stream diffusing means in fixed relationship therewith, which device is adapted to convenient detachable assembly with a pilot burner.

Other objects and advantages will appear from the following complete description and accompanying drawing.

In the drawing,

Fig. 1 shows a pilot burner of conventional construction having assembled therein an orifice spud constructed in accordance with present invention;

Fig. 2 is an enlarged side view of the orifice spud shown in Fig. 1, having portions broken away to more clearly illustrate;

Fig. 3 is a left end view of the orifice spud shown in Fig. 2;

Fig. 4 is a right end view of the orifice spud shown in Fig. 2; and

2

Fig. 5 is an exploded sectional view of the orifice spud shown in Fig. 2.

The orifice spud consists of a body portion 10 which may be turned from a length of hexagonal stock. The body 10 has an externally threaded portion 11 adapted to be threadably engaged in an internally threaded end portion of a pilot burner, and a rearward externally threaded portion 12 adapted to be threadedly engaged by a conventional conduit clamping nut 13. Between the threaded portions 11 and 12, the body is hexagonal. The body is further provided with a bore 14, a rear end counterbore 15 which receives the end of the fuel conduit 16, a forward counterbore 17 which receives a thin orifice plate 18 and a washer-like spacer 19. Rigidly attached to the spacer 19 is a diffusing bar 20. The diameters of the orifice plate 18 and the spacer 19 are such as to nicely fit the counterbore 11. The forward end of the body 10 is reduced in diameter as indicated at 21, thereby leaving a thin wall 22 for the length of the counterbore 17.

The orifice plate 18 and the spacer 19, together with its attached diffusion bar 20, are assembled in the counterbore 17, and the thin wall 22 is then spun over at its outer end to hold these members in rigid assembly with the body member, as shown in Fig. 2 of the drawing. The diffusion bar 20 may be of any sectional configuration; presently, however, I prefer to use an inexpensive length of polished round wire of non-corrosive metal. The periphery and internal diameter of the washer-like spacer 19 are concentric, and the bar 20 extends across the exact center of the central perforation and is attached at its ends to the spacer by welding. The bar 20 is slightly shorter than the diameter of the spacer so as to permit the formed over wall 22 to lie against the face of the spacer at all points. The orifice plate 18 has an orifice 18a which is also concentric with the periphery of the orifice plate. It will be seen that with the above described arrangement, an accurate and uniform relationship, both laterally and longitudinally, between the orifice 18a and the diffusion bar 20 may be readily maintained by the usual manufacturing methods.

The illustrated pilot burner has a lower elongated body member 23 having a through bore 24, and a lower end counterbore 25 which is internally threaded to receive the threaded portion 11 of the above described orifice spud. The

burner body member is also provided with primary air openings 26, entering the chamber formed by the counterbore 25. Attached to the upper end of the body member 23 is a hollow elongated burner head 27 having burner ports 28.

In operation

As fuel issues from the orifice 18a, it strikes the diffusion bar 20 and is, therefore, diverted, causing greater dispersion of the fuel in the air entering ports 26 and, therefore, causing a more thorough mixture of fuel and air entering and "filling" the passage 24 and the hollow burner 27 in which the fuel and air are further mixed. Without such diffusing means, the fuel stream passes through a greater portion of the passage 24 without "filling the passage," in the sense that velocities are relatively extremely high at the center of the fuel stream and extremely low near the walls. As a result of this condition, the injected air "blankets" the fuel stream, and is, therefore, not sufficiently mixed. Also, as fuel velocities are increased without the diffusing means, this condition becomes more pronounced, and when a certain velocity is reached, a lifting of the flame at the burner port results.

With the provision of the above described diffusing means, however, a "choking" effect is achieved which not only improves the mixing of the fuel and air at all velocities, but also reduces mixture velocities and, therefore, permits the operation of the burner at higher fuel velocities without lifting of the flame at the port.

The foregoing description is intended to be illustrative, not limiting, the scope of the invention being set forth in the appended claims.

I claim:

1. A fuel metering device for use in gaseous fuel pilot burners, comprising a body member having a fuel passage therethrough, a counterbore at the outlet end of said fuel passage, and a circular orifice plate having a single concentric central metering orifice and being slidably received in said counterbore, a cylindrical spacer

member having a concentric central passageway therethrough, being slidably fitted in said counterbore and overlying said orifice plate in face to face contact therewith at one end, a transverse diffusing bar welded to the other end of said spacer and lying across the center thereof so as to bisect said metering orifice, and means for rigidly retaining said orifice plate and said spacer fixed in said counterbore.

10. 2. A fuel metering device for use in gaseous fuel pilot burners, comprising an elongated body member having an externally threaded portion for detachable assembly with a pilot burner, said body member having a longitudinal fuel passageway therethrough, a counterbore at the outlet end of said passageway, a circular orifice plate having a single concentric central metering orifice and being slidably received in said counterbore, a cylindrical spacer member having a concentric central passageway therethrough and being slidably fitted in said counterbore and overlying said orifice plate in face to face contact therewith at one end, a transverse diffusing bar rigidly attached to the other end of said spacer and lying across the transverse center thereof so as to bisect said metering orifice, and means for rigidly retaining said orifice plate and said spacer in said counterbore.

JAMES A. WRIGHT.
